CLAIM

The ornamental design for a cooktop substantially as shown and described.

DESCRIPTION

FIG. 1 is a top view of a first embodiment of our new design for a cooktop;

FIG. 2 is a top view of a second embodiment of our new design for a cooktop;

FIG. 3 is a top view of a third embodiment of our new design for a cooktop; and,

FIG. 4 is a top view of a fourth embodiment of our new design for a cooktop.

The portions of the cooktop shown in broken line form no part of the claimed design. The broken line cookware shown in the figures depicts environment and forms no part of the claimed design. The appearance of the cooktop transitions between the images shown in FIGS. 1-4. The process and period in which one image transitions to another image forms no part of the claimed design.

1 Claim, 4 Drawing Sheets(56)
